UNITED STATES PATENT OFFICE.

HENRY CLAY FORSHAY, OF NEW YORK, N. Y.

FOLDING CHAIR.

No. 911,226.

Specification of Letters Patent.

Patented Feb. 2, 1909.

Application filed February 28, 1908. Serial No. 418,300.

To all whom it may concern:

Be it known that I, HENRY CLAY FORSHAY, a citizen of the United States, residing at the city of New York, in the county of New York and State of New York, have invented new and useful Improvements in Folding Chairs, of which the following is a specification.

Folding chairs, are useful in transportation and for large assemblages, also because 10 of the small space they occupy when folded, nested, or packed together and not in use.

My invention relates to improvement in folding chairs, where the legs, backs, or seats are foldable, and a flexible or textile seat 15 may be used.

The object of my improvement is to provide a folding chair, of very simple, durable, and economic construction, light in weight, and yet very strong, and very compact when 20 folded.

The folding chairs are specially suited for manufacturing in large quantities on account of their simplicity and cheapness.

My improvement also makes the folding 25 chair, practically noiseless on opening and closing, and also prevents two or more of the folding chairs from chafing and scratching each other when nested or packed together.

In my improvement I provide a self-acting 30 seat roller, whereon a flexible or textile seat is automatically rolled when the chair is folded, and automatically unrolled when the chair is opened. The construction is such as to enable the self-acting seat roller with the 35 seat rolled thereon, and the legs of the folding chair to be folded flush entirely within the dimension of the back-frame of the chair, thereby reducing the bulk of the chair to the minimum, and rendering it more conveniently portable than is possible with any of 40 the other folding chairs having flexible or textile seats attached thereto. I also supply in my improvement a detachable secondary and strengthening back-rest, that may be 45 upholstered if desired.

In my improvement I attach the flexible seat to the seat cross-bar, and the self-acting seat roller by means of separable hinges and they are so constructed as to allow the seat 50 to be replaced with another in a very few moments.

The bottom cross-bar of the back-frame is so constructed in my improvement that it takes up all the side strains on the legs, 55 and back-frame, and adds greatly to the

strength, and durability of the folding chair thereby, and it also will prevent the squeaking sound usually heard, when using folding chairs having the back-frame pivoted to the legs.

My improvement supplies a folding chair that can be opened and folded from either the top or bottom ends, and if the user so desires the folding chair will automatically fold of itself, simply by the act of lifting the 60 chair clear of the ground, also by drawing the chair backward upon the rear legs when the self-acting seat roller is at its ordinary tension, thereby allowing two of the chairs to be 65 folded at the same time, one with each hand, 70 and allowing the user to fold the maximum number of the chairs in a given time.

My improvement consists in a certain construction and arrangement of the parts as hereinafter more fully set forth, the essential 75 features of which being pointed out particularly in the claims.

I attain these objects by means illustrated in the accompanying drawing in which—

Figure 1 is a general view in perspective of 80 my improved folding chair, with the flexible seat attached; Fig. 2, is a front elevation of the folding chair when folded with the seat rolled upon the self-acting seat roller; Fig. 3, 85 is a side elevation of Fig. 2; Fig. 4, is a front elevation of the side-bars and the main back rest of the back-frame on the line 1 1, of Fig. 1; Fig. 5, is a vertical cross-section of the cross-bar H, on the line 2 2, of Fig. 6; Fig. 6, 90 is a vertical front elevation of the legs a a, with the cross-bar H, and the seat roller B, 95 attached, reversed, upper ends down on line 3 3, of Fig. 2; Fig. 7, is a vertical cross section of the back-rest on the line 4 4, of Fig. 4, with a vertical cross section of one of the front legs a a; Fig. 8, is a vertical cross section of the main and secondary and strengthening back-rest on the line 5 5, of Fig. 1; Fig. 9, is a vertical cross section of the bottom cross-bar of the back-frame on the 100 line 6 6, of Fig. 1; Fig. 10, is a vertical cross section of the seat cross-bar with the hinge and a section of the seat attached on the line 7 7, of Fig. 1; Fig. 11, is a vertical cross section of the outer casing of the self-acting seat 105 roller showing the half hinge attached.

Similar letters refer to similar parts throughout the several views.

a a, and b b, constitute the front and rear legs of the folding chair, the legs a a, having 110

the same depth, but being longer than the legs $b b$, as shown in Fig. 2; the front extensions of the rear legs $b b$, are joined together by the seat cross-bar G , and at any desired 5 distance from the lower ends by the cross-bar f ; the front legs $a a$, are pivoted centrally to, and at the same distance from the lower ends of the legs $b b$, as from the lower ends of the legs $a a$, by the pivots $g g$. When 10 the legs $a a$, and the legs $b b$, are folded together, the rear extensions of the front legs $a a$, being longer than the front extensions of the rear legs $b b$, will extend beyond the seat cross-bar G , and the front extensions of the 15 rear legs $b b$, and the legs $a a$, and $b b$, will be in line and flush with each other, front, rear, and at the lower ends as shown in Fig. 2. On the upper or inner side of the front extensions of the rear legs $b b$, and at the desired 20 distance below the seat cross-bar G , I have the recesses $e e$, and on the rear or under side of the rear extensions of the legs $a a$, and at the same distance from the pivots $g g$, as the recesses $e e$, on the front extensions of the 25 rear legs $b b$, and of the same depth as the recesses $e e$, I have the cross-bar H , that will inclose in the recesses $e e$, and act as a stop when the legs $a a$, and $b b$, are folded together, and be flush with each pair of legs as 30 shown in Fig. 2.

On the inner side of the cross-bar H , and where it strikes into the recesses $e e$, I have the sound deadening cushions $y y$, as shown in Figs. 5 and 6, which I may make of felt or 35 similar material. I preferably use soft rubber, which I secure into the holes having beveled edges in the cross-bar H . When the chair is open the cushions will protrude above the surface of the cross-bar H , as 40 shown in Fig. 5, and deaden the sound when the cross-bar H , strikes into the recesses $e e$. When the legs are folded and closely pressed together the rubber cushions $y y$, will spread and swell into the beveled portions of the 45 holes and be flush with the surface of the cross-bar H , as shown in Fig. 7, allowing the legs $a a$, and $b b$, to be in line and flush with each other. For the better protection of the chair, I duplicate the cushions $y y$, on the 50 other outer side of the cross-bar H , with the cushions $x x$, as shown in Figs. 2, 3 and 5, as above preventing cushions. I preferably continue the holes and the cushions $y y$, entirely through the cross-bar H , as shown in 55 Figs. 5 and 7. When two or more chairs are packed together the above preventing cushions will rest against the outer side of the legs of the other chair and protect the chairs from chafing and scratching each other.

60 To the rear extensions of the front legs $a a$, I pivot centrally thereto the side-bars $c c$, of the back-frame of the same depth as the legs $a a$, and $b b$, with the pivots $h h$. Near the upper ends I join the side-bars $c c$, 65 of the back-frame with the back-rest F , and

at the lower ends I join the side-bars $c c$, with the bottom cross-bar E , as shown in Figs. 1 and 2. The location of the pivots $h h$, in the side-bars $c c$, and the legs $a a$, are determined by the inclination of the back-frame desired. On the upper side and near the lower ends of the front legs $a a$, I have the recesses $d d$, similar to the recesses $e e$, and on the under side and near the lower ends of the rear legs $b b$, I have the recesses $i i$, similar to the recesses $d d$, as shown in Fig. 1. When the back-frame of the chair is pressed forward over and beyond the seat cross-bar G , and downward, the back-rest F , will enter into the recesses $d d$, near the lower ends of the front legs $a a$, and the cross-bar E , of the back-frame will extend beyond and inclose the rear extensions of the front legs $a a$. When in that position the chair is raised from the ground by the handle o , of the bottom cross-bar E , of the back-frame, and the legs $a a$, and $b b$, are folded together. The recesses on the lower ends of the legs $b b$, will overlap the back-rest F , the cross-bar H , will enter into the recesses $e e$, on the front extensions of the rear legs $b b$, and the chair will be folded entirely within the dimensions of the back-frame. The outer surfaces of the back-frame and the legs of the folding chair will be in line and flush with each other, the ends of the legs overlapping the back-rest F , and the rear and front extensions of the legs being within the inclosure of the cross-bar E , as shown in Fig. 2.

Manifestly to have the back-frame of my 100 chair at its greatest inclination the bottom cross-bar E , of the back-frame will rest against the rear extensions of the front legs, or upon the rear legs, and against the rear extensions of the front legs, both at the 105 same time when the chair is open, simply by lowering the pivots $h h$, in the side-bars of the back-frame, and placing them higher in the rear extensions of the front legs, and the chair will fold as described without departure from my invention, but I prefer the cross-bar resting only on the rear legs, as shown in Fig. 1, because of the increased 110 strength and steadiness of the chair gained thereby.

On the back-rest and where the recesses of the front legs $a a$, strike against it, I have the sound deadening and chafe preventing cushions $j j$, and $k k$, as shown in Figs. 4 and 7, similar in all respects to the cushions $y y$, and $x x$, made in the same manner and for the same purposes. The sound deadening cushions $y y$, on the cross-bar H , being in the recesses $e e$, prevent the recesses $i i$, in the lower ends of the legs $b b$, from striking the back-rest F , until the whole chair is folded and pressed tightly together, and when two or more of the chairs are packed together the chafe preventing cushions $k k$, and $x x$ will rest against the outer side of 130

the legs of the other chair, and prevent the chairs from chafing and scratching each other.

For the purposes of more strengthening and stiffening the back-rest F, and when desired, supplying a neat and economically upholstered back-rest, I use the detachable secondary back-rest I, as shown in Figs. 2 and 8, which I attach to the back-rest F, in 5 the vacant space between the legs when the chair is folded, by the screws in the rear of the back-rest F, as shown in Fig. 1, or by other means. Obviously, I may have the back-rest F, and the strengthening back-rest I, of one piece of material and have improvement to the folding chair. On the under or inner side of the secondary back-rest, I may have the groove or gutter r, parallel with and close to the continuous 10 edge for the purpose of receiving the nails that hold the material that the secondary back-rest may be upholstered with thereby allowing it to be more evenly and closely secured against the main back-rest F. I may 15 also continue the hand-hole s, of the main back-rest entirely, or partly through the secondary back-rest as shown in Fig. 8.

For the purposes of making the whole chair stronger and more steady, therefore 20 more durable, I have where the bottom cross-bar E, strikes against the rear legs b b, the circumferential recesses m m. When the chair is open the rear legs b b, will enter into and engage with the recesses m m, as shown 25 in Fig. 1, and will prevent the side strain on the legs and the back-frame of the chair. I may have flat recesses or cut-outs on the cross-bar E, where it strikes the legs and still retain improvement to the chair, but I 30 prefer the circumferential recesses because of the lesser friction. To deaden the sound and prevent the chafing of the rear legs b b, where the cross-bar E, strikes them, I have the circumferential cushions n n, in the recesses m m, preferably made of felt. The 35 cushions may be flush with the recesses, but I prefer them not quite filling the same, as shown in Fig. 9.

The back-frame having the cross-bar E, 40 with the recesses m m, and with, or without the cushions n n, may be applied as well to the folding chairs where the bottom cross-bar will rest against the rear extensions of the front legs, or upon the rear legs, and against the rear extensions of the front legs, both at the same time.

To the ends of the rear extensions of the front legs I attach the self-acting seat roller B, as shown in Figs. 1, 2 and 6, preferably 45 made of metal on which the flexible or textile seat A, will roll closely, evenly and silently automatically when the chair is being opened or folded together. I attach the seat roller to the rear extensions of the front legs by means of the pins v v, passing

through the spindle of the seat roller as shown in Fig. 1. I may accomplish the same by other common methods. I make no claim as to the mechanism of the self-acting seat roller, as I may use any of the old and well known means of revolving the roller to accomplish my object of supplying a self-acting seat roller.

To the self-acting seat roller B, I attach the rear end of the flexible or textile seat A, and to the seat cross-bar G, I attach the front end of the seat A. I may attach the seat to the self-acting seat roller by tightly sewing it around or cementing it to the roller, or both, or by any other known method. I may attach the seat to the seat cross-bar by nails, screws, or any of the other well known means. In my improvement I attach the rear end of the seat to the self-acting seat roller by means of the hinge D. I may attach 75 the hinge to the self-acting seat roller by solder, or other means, or I may have the outer casing of the roller and a half hinge made of one piece of metal to serve as half of the hinge D, as shown in Fig. 11. I attach the 80 front end of the seat to the seat cross-bar by means of the hinge C, as shown in Figs. 1, 2 and 10. I use for the hinges D and C, the 85 separable hinges having doubled or folded leaves, as they are stronger and more suitable 90 for my purposes than the single leaf, or an inseparable hinge. Near the longitudinal edges of the hinges, I have perforations for the purpose of attaching to the seat cross-bar and the flexible seat, as shown in Figs. 1 95 and 2.

I attach the ends of the seat in between the doubled or folded leaves of the hinges more securely than is possible with the hinges having single leaves. The hinges D and C, are 100 separable and so constructed that the spindles p and q, connecting the two halves of each of the hinges D and C, may easily be withdrawn. The spindle p, in the self-acting seat roller hinge D, may be withdrawn 105 through the small holes t t, below the self-acting seat roller spindle ends in the ends of the rear extensions of the legs a a, without removing the seat roller, as shown in Fig. 1. Otherwise to change the tension of the self-acting seat roller it would be necessary to remove the seat from the seat cross-bar, and, to renew the seating it would be necessary to remove the seat roller from the chair. By being enabled to remove the spindles p and q, 110 a new seat may be attached to the chair in place of the old one in a few moments. The new seat being supplied with the half hinges attached thereto, I may attach the hinges or half hinges to the seat cross-bar by nails, 115 screws, or other means.

In the front and rear ends of the flexible or textile seat I may place the untearable strips l l, as shown in Fig. 10, for the purposes of preventing the seat from tearing away from 120 125 130

the seat fastenings of the hinges. Also for dividing the strain evenly longitudinally along the front and rear edges of the seat, I may also place in the side edges or hems of the seat the untearable overlapping flexible strips *z z*, as shown in Fig. 10, to divide the strain evenly along the side edges of the seat, also to prevent any tearing or cutting of the edges of the seat from passing beyond the said untearable overlapping strips. The overlapping strips will slide one upon the other in the stretching rolling, and unrolling of the said flexible seat.

Ordinarily the tension of the self-acting seat roller is fixed so that it will allow the chair to be raised from the ground by the hand hole *s*, in the back-rest *F*, or the handle *o*, on the cross-bar *E*, without the seat rolling up, the flexible seat rolling up, only, upon the folding of the legs *a a* and *b b*, together. When a large number of the chairs are to be folded very rapidly, the spindle in the hinges *D* or *C*, may be removed and a few turns of the self-acting seat roller in the proper direction will tighten the tension sufficiently. When the spindle is replaced in the hinge the weight of the chair, and the spread of the crossed legs will keep the chair open. To fold the chairs rapidly the back-frame is thrown forward slightly, and it will fall of its own weight over and beyond the front of the seat, and the back-rest will fall into the recesses *d d*, on the front legs *a a*, the cushions in the back-rest deadening the sound. When the chair is tilted backward on the rear legs, or lifted from the ground by the handle *o*, on the cross-bar *E*, the entire chair will fold together silently and automatically. Practically the action of drawing backward or lifting the chair folds it up, and will allow one person to fold two of the chairs at the same time, one with each hand.

I may use in place of the self-acting seat roller, any ordinary roller, or cross-bar, with any ordinary flexible or textile seat attached thereto, and still retain improvement to and usefulness of the folding chair.

Having thus described my invention what I claim as new, and desire to secure by Letters Patent, is—

1. The combination in a folding chair, the cross-bar on and in the rear of the rear extensions of the front legs, the recesses on and in the rear of the front extensions of the rear legs, the side-bars of the back-frame pivoted to the rear extensions of the front legs, said side-bars being connected at the upper ends by the back-rest, the lower ends being connected by the cross-bar, said cross-bar resting on the rear legs when the chair is open, and the recesses near the lower ends of the front and rear legs, said recesses overlapping the back-rest of the back-frame, and the bottom cross-bar of the back-frame folding beyond and inclosing the upper extensions of the legs when the chair is folded substantially as set forth.

of the legs when the chair is folded substantially as set forth.

2. The combination in a folding chair, the cross-bar on and in the rear of the rear extensions of the front legs, the recesses on and in the rear of the front extensions of the rear legs, the seat roller attached to the rear extensions of the front legs, the flexible seat connected to the seat roller and the seat cross-bar by the separable hinges, and the side-bars of the back-frame pivoted to the rear extensions of the front legs, said side-bars connected at the upper ends by the back-rest, the lower ends connected by the cross-bar, said cross-bar resting on the rear legs when the chair is open, and the recesses near the lower ends of the front and rear legs, said recesses overlapping the back-rest of the back-frame, and the bottom cross-bar of the back-frame folding beyond and inclosing the upper extensions of the legs when the chair is folded substantially as set forth.

3. The combination in a folding chair, the side-bars of the back-frame pivoted to the rear extensions of the front legs, said side-bars being connected at the upper ends by the back-rest, the lower ends being connected by the cross-bar, said cross-bar having the circumferential recesses, said recesses resting against and engaging with the rear legs when the chair is open, substantially as set forth.

4. The combination in a folding chair, the side-bars of the back-frame pivoted to the rear extensions of the front legs, said side-bars being connected at the upper ends by the back-rest, the lower end being connected by the cross-bar, said cross-bar having the circumferential recesses, and the circumferential sound deadening cushions surrounding the cross-bar in said recesses, said cushions striking against and the recesses engaging with the rear legs when the chair is open, substantially as set forth.

5. The combination in a folding chair, the cross-bar on and in the rear of the rear extensions of the front legs having the sound deadening cushions, the recesses on and in the rear of the front extensions of the rear legs, said cushions striking against the legs when the cross-bar enters into the recesses, the side-bars of the back-frame pivoted to the rear extensions of the front legs, said side-bars being connected at the upper ends by the back-rest, said back-rest having the sound deadening cushions, the lower ends being connected by the cross-bar, said cross-bar resting on the rear legs when the chair is open, the recesses near the lower ends of the front and rear legs, said recesses overlapping the back-rest of the back-frame and the front legs striking against the cushions thereon, the cross-bar of the back-frame folding beyond and inclosing the upper extensions of the legs when the chair is folded substantially as set forth.

6. The combination in a folding chair, the cross-bar on and in the rear of the rear extensions of the front legs, the recesses on and in the rear of the front extensions of the 5 rear legs, the side-bars of the back-frame pivoted to the rear extensions of the front legs, said side-bars being connected at the upper ends by the back-rest, and the secondary and strengthening back-rest attached to the said back-rest, the lower ends being connected by the cross-bar, said cross-bar resting on the rear legs when the chair is open, and the recesses near the lower ends of the front and rear legs, said recesses overlapping the back-rest of the back-frame, and the bottom cross-bar of the back-frame folding beyond and inclosing the upper extensions of the legs when the chair is folded, substantially as shown and described. 70

10 9. The combination in a folding chair, the seat roller attached to the rear extensions of the front legs, and the flexible seat connected to the seat roller and the seat cross-bar by the separable hinges, and the side-bars of the back-frame pivoted to the rear extensions of the front legs, said side-bars connected at the upper ends by the back-rest, and the secondary and strengthening back-rest attached to the said back-rest, and the lower ends connected by the cross-bar, said cross-bar resting on the rear legs when the chair is open, and the recesses near the lower ends of the front and rear legs, said recesses overlapping the back-rest of the back-frame, and the lower ends of the legs inclosing the side ends of the secondary and strengthening back-rest, and the cross-bar of the back-frame folding beyond and inclosing the upper extensions of the legs when the chair is folded, substantially as set forth. 80 85

15 7. The combination in a folding chair, the cross-bar on and in the rear of the rear extensions of the front legs having the sound deadening cushions, said cushions extending through the said cross-bar and forming chafe preventing cushions in the rear thereof, the recesses on and in the rear of the front extensions of the rear legs, said sound deadening 20 cushions striking against the legs when the cross-bar enters into the recesses, the side-bars of the back-frame pivoted to the rear extensions of the front legs, said side-bars being connected at the upper ends by the back-rest, said back-rest having the sound deadening cushions, said cushions extending through the said back-rest and forming chafe preventing cushion in the rear thereof, the lower ends of the said side-bars being 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

8. The combination in a folding chair the seat roller attached to the rear extensions of the front legs, and the flexible seat connected to the seat roller and the seat cross-bar by the separable hinges, and the side-bars of the back-frame pivoted to the rear extensions of the front legs, said side-bars connected at the upper ends by the back-rest and the lower ends connected by the cross-bar, said cross-bar resting on the rear 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

cushions, in the rear thereof, and the secondary and strengthening back-rest attached to the said main back-rest, and the lower ends of the side bars being connected by the cross-bar, having the circumferential recesses, said cross-bar resting on the rear legs when the chair is open, and the recesses near the lower ends of the front and rear legs, said recesses striking against the sound deadening 10 cushions on the main back-rest and overlapping the said main back-rest, and the lower ends of the legs inclosing the side ends of the secondary and strengthening back-rest, and the bottom cross-bar of the back-frame folding 15 beyond and inclosing the upper extensions of the legs when the chair is folded, the chafe preventing cushions in the rear of the main back-rest, and the chafe preventing cushions in the rear of the leg cross-bar protecting 20 the chair front and rear from the chafing of the next chair when two or more of the chairs are packed or nested together, substantially as shown and described.

12. The combination in a folding chair, 25 the side-bars pivoted to the rear extensions of the front legs, said side-bars connected at the upper ends of the back-rest, and the

strengthening back-rest attached to the said back-rest, and the recesses at the lower ends of the front and rear legs, said recesses overlapping the main back-rest, and the lower ends of the legs inclosing the side ends of the strengthening back-rest when the chair is folded, substantially as set forth.

13. The combination in a folding chair, 30 the side-bars of the back-frame pivoted to the rear extensions of the front legs, said side-bars connected at the upper ends by the back-rest, and the strengthening back-rest attached to the said back-rest, and the lower 35 ends of the side bars connected by the cross-bar, the lower ends of the front and rear legs folding between the side ends of the strengthening back-rest and the side-bars of the back-frame when the chair is folded, substantially as set forth.

In testimony whereof I have signed my name to this application in the presence of two subscribing witnesses.

HENRY CLAY FORSHAY.

Witnesses:

ROBERT McDONALD,
JOHN B. LOTZ.
